CLAIM

The ornamental design for a mobile communication terminal, as shown and described.

DESCRIPTION

FIG. 1 is a perspective view of a mobile communication terminal of the claimed design.

FIG. 2 is a front elevation view of the mobile communication terminal of FIG. 1.

FIG. 3 is a rear elevation view of the mobile communication terminal of FIG. 1.

FIG. 4 is a left side elevation view of the mobile communication terminal of FIG. 1.

FIG. 5 is a right side elevation view of the mobile communication terminal of FIG. 1.

FIG. 6 is a top plan view of the mobile communication terminal of FIG. 1.

FIG. 7 is a bottom plan view of the mobile communication terminal of FIG. 1; and,

FIG. 8 is a front elevation of the mobile communication terminal of FIG. 1 with its upper cover opened.
